FEEDING MECHANISM FOR SLICING MACHINES

Joseph Folk, La Porte, Ind., assignor to U. S. Slicing Machine Company, La Porte, Ind., a corporation of Indiana

Application April 2, 1934, Serial No. 718,582

10 Claims. (Cl. 146—102)

This invention relates to slicing machines, and particularly to feeding mechanism for slicing machines. More specifically, the invention relates to that type of feeding mechanism used on slicing machines which have a reciprocal carriage and a substance or food pusher which operates at right angles to the movement of the carriage and pushes the substance against a gauge plate.

The primary object of the present invention is to provide new and improved means for moving the pusher plate only when the substance on the food carriage is directly opposite the gauge plate.

Another object of the invention is to provide slicing machine feeding mechanism which comprises normally inactive means which are rendered active when the carriage is moved to a predetermined position relative to the position of the slicing machine, whereby the said means will become operative and move the substance against the gauge plate and then remain inactive or inoperative until the carriage again attains a predetermined position.

A further object is to provide feeding mechanism which feeds the substance a predetermined distance, and then remains inactive or inoperative to prevent further movement of the substance toward the cutting plane of the knife during reciprocation of the substance across the knife, and thereby prevent smearing of the knife by the substance and overcome undue friction.

Numerous other objects and advantages will be apparent throughout the progress of the following specification.

The accompanying drawings illustrate a selected embodiment of the invention, and the views therein are as follows:

Fig. 1 is a detail plan view of an improved slicing machine, and embodying the invention.

Fig. 2 is a detail elevation of the slicing machine shown in Fig. 1 looking in the direction from the operator's stance.

Fig. 3 is a detail longitudinal section taken on the lines 3—3 of Figs. 1 and 2.

Fig. 4 is a detail plan section showing the position of the parts during the forward movement of the carriage.

Fig. 5 is a similar view showing some of the mechanism controlled by a cam positioned at the end of the machine toward the operator.

Fig. 6 is a detail plan section showing the position of the operating rod which causes movement of the pusher plate.

Fig. 7 is a detail sectional view on the lines 7—7 of Figs. 4 and 5.

The particular slicing machine herein shown comprises a base 1, over which the undertable 2 and carriage 3 is adapted to be reciprocated. The carriage 3 is mounted in suitable guide means 4, 4 rigidly supported by the base 1. A knife 5 carried by a knife support bracket 6 is rotated by means of a motor 7. A gauge plate 8 is mounted to the left of the food or substance supporting surface 9, and is movable laterally so that its substance supporting face 10 will lie in a plane parallel to the plane of the cutting knife 5.

The gauge plate 8 is movable by means of the knob 11 to properly position the gauge plate into proper relationship to the cutting blade of the knife. The gauge plate and the manner in which it is operated or controlled is well known in this art, and further description thereof will not be made.

The carriage 3 including its food table 9 is manually reciprocated forwardly and rearwardly by means of a handle 12. A slice receiving plate or tray 13 is positioned to the lefthand side of the machine to receive the slices which are cut from the substance by the knife 5. A transverse rod 14, Figs. 3, 4 and 5, is rigidly supported to the undertable 2, and has a slide bearing 15 slidably mounted thereon. A pusher plate 16 has an operating arm 17 which is fastened by screws 18 to a flange on the slide bearing 15. A roller or slide 19, Fig. 3, is fastened to the pusher plate, and this roller and the slide rod 14 constitute a guiding means for the pusher plate in its movement at right angles to the movement of the carriage and toward the cutting edge of the knife. A friction plug 20, Fig. 4, is arranged in a boss 21 formed on the slide bearing, and this plug is adapted to ride along the surface of the rod 14, there being a compression spring 22 mounted behind the friction plug to create a certain amount of friction or sluggishness in the movement of the slide bearing 15 or pusher plate 16 to prevent movement of the pusher by jar or by the pulling of the knife on the substance or by other accidental forces. A projection 23 is formed on the undertable 2, upon which there is pivoted a plate 24 by means of a pivot 25, Figs. 3 and 4. A spring 26 is fastened to a pin 27 on the plate 24, and to a pin 28 formed on the undertable 2 and normally tends to urge the plate 24 to the right, Figs. 4 and 5. A roller 29 is fastened by a pin 30 to the extreme end of the plate 24. This pin 30 is formed with an enlarged

shoulder 31 which loosely fits in an oblong slot 32 in the undertable 2.

A cam 33 having a cam surface 34 is mounted by screws 35 to the upper surface of the frame 1 of the slicing machine. When the undertable 2 is moved from the end of the cutting stroke toward the operator and the roller 29 approaches the cam 33 and engages the cam surface 34, the plate 24 will be moved to the left, against the tension of the spring 26, from the position shown in Fig. 4 to the position shown in Fig. 5. At the beginning of the cutting stroke, that is, the forward movement of the carriage, the roller 29 will disengage the cam 33, and the plate 24 will be returned to its normal original position (Fig. 4) by the tension spring 26.

A slide rod 36 having ratchet teeth 37 is mounted in bosses 38 and 39 fixed to the undertable 2. These bosses provide bearings for the slide rod. This rod 36 has a pin 40 fixed thereto which is guided in a slot 41 formed in the boss or bearing 39. The slide rod 36 is adapted to have limited slideable movement in the bosses or bearings 38 and 39, but is prevented from rotating due to 25 the pin and slot connection 40 and 41, respectively.

A roller 42 is fastened to the slide rod 36 by a pin 43, and a block 44 is fastened by suitable pins 45 to the plate 24. A tension spring 46 has one end fixed to the plate 24 as indicated 30 at 47, and its other end to the pin 40. The spring 46 is adapted to pull the slide rod 36 to the left, Figs. 4 and 5, and the plate 24 to the right to make contact between the roller 42 and the block 44. When the roller 29 on the plate 35 24 contacts with the cam surface 34 of cam 33, the plate 24 is pivoted on its pivot screw 25 and causes the slide rod 36 to move simultaneously with the plate 24 and in the same direction.

The slide bearing 15 is formed with an arm 48 into which there is threaded a hollow stud 49 backed by a nut 50, Fig. 7. One end of the stud 49 is provided with a slot 51 and guides a pin 52 which guides a plug 53 having a tooth 54, Fig. 7. The tooth 54 is adapted to engage the teeth 37 on the slide rod 36, there being a spring 55 arranged in the recess 56 in the stud 49. This spring 55 is adapted to urge the plug 53 toward the slide rod 36 so as to keep the tooth 54 in engagement with one of the ratchet teeth 37 on 50 the slide rod 36. A handle 57 is integrally formed with the plug 53, and is adapted to extend forwardly a predetermined distance out of the hollow threaded stud 49. This handle 57 permits the tooth 54 to be retracted from the slide rod 36 55 so that the slide bearing 15 may be slid along the slide rod 14, to the right, Figs. 4 and 5. As the pusher plate 16 is directly connected to the slide bearing 15 by means of the arm 17, the pusher plate 16 will be moved along with the slide bearing 15. Therefore, when the handle 57 60 is pulled outwardly to disengage the tooth 54 from the teeth 36, and the handle 57 shifted to the right, Figs. 4 and 5, the pusher plate 16 will also move to the right.

65 The gauge plate 8 gauges the thickness of the slices to be cut from the substance, and the pusher plate 16 fastened to the slide bearing 15 pushes the substance against the gauge plate. When the roller 29 on the plate 24 engages the cam surface 34, the tension of the spring 46 will pull the slide rod 36 to the left from the position shown in Fig. 4 to the position shown in Fig. 5. Since the teeth 37 are cut along one side of the rod 36, they are always in contact with the tooth 54, 70 which is fastened to the plug 53 on the slide

bearing 15. Therefore, slideable movement of the slide rod 36 to the left, Figs. 4 and 5, will cause slideable movement of the slide bearing 15 in the same direction. The slideable movement of the slide rod 36 is stopped when the substance moved by the pusher plate 16 engages the gauge plate 8. When the roller 29 engages the cam face 34 due to the movement of the carriage 3 upon its guide, the roller 29 will force the plate 24 to continue to move to the left, Fig. 4, to the position shown in Fig. 5. The movement of the plate 24 to the left is against the tension of the springs 26 and 46. The movement of the plate 24 to the left causes the block 44 to be moved away from the contacting roller 42 and the pusher plate 15 will be moved through the sliding movement of the rod 36 until the substance on the substance table 9 engages the gauge plate 8. The movement of the pusher plate is caused by the tension of the spring 46 which moves the slide rod 36 20 when the plate 24 is shifted by reason of the roller 29 engaging the cam surface 34. When the substance table 9 is moved forwardly, that is, away from the operator, the roller 29 on the plate 24 will move out of contact with the cam 25 surface 34, and the plate 24 will be returned to its normal position by the spring 26 from the position shown in Fig. 5 to the position shown in Fig. 4. This return movement of the plate 24 will move the block 44 into contact with the roller 30 42 and the slide rod 36 will be again shifted to its normal initial position. However, the return movement of the slide rod 36 will not affect the position of the slide bearing 15 because the tooth 54 will merely slide over the teeth 37 on 35 the slide rod 36. Therefore, when the carriage is moved to a predetermined position, the plate 24 will be shifted because of the engagement of the roller 29 with the cam surface 34. The shifting of the plate 24 on its pivot 25 will cause 40 the spring 46 to shift the slide rod 36 a predetermined distance to the left. The shifting of the slide rod 36 to the left will cause the slide bearing 15 to also shift because of the engagement of the tooth 54 with one of the teeth 37 45 on the slide rod. The shifting of the slide rod 36 is governed by the thickness of a slice, that is, the slide rod 36 will shift a predetermined distance to the left until the substance on the substance table being pushed by the pusher 16, engages the gauge plate 8. When the carriage 3 is moved forwardly and the roller 29 is off of the cam surface 34, the spring 26 will return the plate 24 to its normal position, and the block 44 will be moved into engagement with the roller 50 42 and return the rod 36 to its initial position. However, the return movement of the rod 36 will not affect the slide bearing 15 nor will it move this slide bearing 15, because the teeth 37 on the slide rod 16 will slide over the tooth 54. 60

The parts are so constructed so that the cam 34 will cause the roller 29 to move a distance greater than the greatest thickness of a slice. Therefore, there will always be some idle movement in the plate 24, which movement is measured by the gap between the block 44 and the roller 42. Therefore, if the maximum movement of the roller 29 is for instance 1 inch, and the maximum thickness of a slice to be cut is $\frac{3}{4}$ inch, the gap between the block 44 and the roller 42 70 will be $\frac{1}{4}$ inch. If, however, only a $\frac{1}{4}$ inch slice is to be cut, and the maximum movement of the roller 29 remains the same (1 inch), the gap between the block 44 and the roller 42 will be $\frac{3}{4}$ inch. 75

The movement of the plate 24 may be restricted or limited by the length of the slot 32. However, the movement of the plate 24 can be limited in several ways, for instance, the shoulder 5 31 on the pin 30 could stop against the outer end of the slot 32, or the pin 40 could be stopped by the end of the slot 41, or the end of the slide rod 36 could be stopped against the bottom of bearing or boss 39.

10 It is preferable to allow for a little clearance between the shoulder 31 of pin 30 and the slot 32, as well as a little clearance between the pin 40 and the end of the slot 41 so that the end of the slide rod 36 may be adjusted relative to the 15 bottom of the boss or bearing 39, and therefore, through this adjustment cause the roller to always be in proper adjusted position relative to the cam surface 34.

10 The boss 39 may be made slidable in respect 20 to the undertable 2 as shown in Fig. 6. In this figure, the boss 39 is slidably inserted in the web of the undertable as indicated at 59, Fig. 6. A fiber plug 60 may be inserted in the end of the boss to provide an abutment against which the 25 end 61 of the slide rod 36 may engage. The fiber plug 60 may be secured to the boss 39 by means of a pin 62. A set screw 63 is threaded into the undertable and engages the boss 39 to hold the boss in its proper adjusted position.

30 The front of the carriage, Fig. 2, is provided with a slot 64 to permit the handle 57 to be operated to manually shift the slide bearing 15.

35 The invention provides a simple efficiently operated means for preventing the movement of the substance during reciprocation of the carriage, and thereby reduces the amount of smear which would otherwise be caused by the substance being continually urged toward the knife. The spring pressure which advances the substance 40 against the gauge plate is only active while the substance is opposite to gauge plate, and then only while the substance is to move a short distance over the gauge plate. A great amount of smear caused by the substance under pressure 45 rubbing over the gauge plate and knife is prevented. The construction herein disclosed prevents continual urging of the substance toward the cutting plane of the knife or against the knife, and therefore, no brake means are required to 50 overcome or prevent the urging action of the spring during normal reciprocation of the carriage. The present invention provides means which are normally inactive, and are rendered active only at a predetermined period covering 55 a very short space of time. In other words, the spring pressure has no effect on the pusher during normal operation. However, when the roller 29 strikes the cam surface 34, the slide rod positively moves the slide bearing 15 and consequently the pusher plate 16. Therefore, there is no constant urging action tending to urge the substance toward the cutting plane of the knife, except that the very commencement of the cutting stroke when the substance is pushed against 60 the gauge plate by the positive movement of the rod, the spring 46 causes the movement of the rod 36 only when the plate 24 is swung on its pivot only by the positive action of the roller and the cam 65 surface 34. As soon as the roller 29 leaves the cam surface 34, the springs 26 and 46 return the plate 24 to its initial position. The invention, therefore, comprises means which are normally inoperative, but which are rendered operative only at a predetermined interval, and for

a very short period. A period, however, is sufficient to cause the substance to come into contact with the gauge plate.

Changes may be made in the form, construction and arrangement of the parts without departing from the invention or sacrificing any of its advantages, and the right is hereby reserved to make all such changes which fall within the scope of the following claims.

The invention is hereby claimed as follows:

1. In a slicing machine having a base, a carriage having a substance supporting surface and adapted to be reciprocated across said base, a rotary knife supported in juxtaposition in relation to the movement of the carriage to cut slices from the substance during reciprocation of the carriage, a gauge plate having a face parallel to the cutting plane of the knife, a pusher plate for shifting the substance along said surface toward the gauge plate, a slide bearing for moving said pusher plate, a rod adapted to shift the slide bearing, a spring connected to the rod to shift the rod when tension is applied to the spring, a pivoted plate to which the spring is connected, a cam mounted on the base and shifting said plate during reciprocation of the carriage, the shifting of said plate putting a tension on the spring, the tension on the spring shifting the rod, and moving the slide bearing and consequently the pusher plate.

2. In a slicing machine having a base, a carriage having a substance supporting surface and adapted to be reciprocated across said base, a rotary knife supported in juxtaposition in relation to the movement of the carriage to cut slices from the substance during reciprocation of the carriage, a gauge plate having a face parallel to the cutting plane of the knife, a pusher plate for shifting the substance along said surface toward the gauge plate, a slide bearing for moving said pusher plate, a rod adapted to shift the slide bearing, a spring connected to the rod to shift the rod when tension is applied to the spring, a pivoted plate to which the spring is connected, a cam mounted on the base and shifting said plate during reciprocation of the carriage, the shifting of said plate putting a tension on the spring, the tension on the spring shifting the rod, moving the slide bearing and consequently the pusher plate, and means for manually disengaging the slide bearing from the rod whereby the slide bearing and consequently the pusher plate may be moved in a direction away from the gauge plate.

3. In a slicing machine having a base, a carriage having a substance supporting surface and adapted to be reciprocated across said base, a rotary knife supported in juxtaposition in relation to the movement of the carriage to cut slices from the substance during reciprocation of the carriage, a gauge plate having a face parallel to the cutting plane of the knife, a pusher plate for shifting the substance along said surface toward the gauge plate, a slide bearing for moving said pusher plate, a rod adapted to shift the slide bearing, a spring connected to the rod to shift the rod when tension is applied to the spring, a pivoted plate to which the spring is connected, a cam mounted on the base and shifting said plate during reciprocation of the carriage, the shifting of said plate putting a tension on the spring, the tension on the spring shifting the rod, moving the slide bearing and consequently the pusher plate, a retractable member carried by the slide bearing for normally locking the slide bearing to the rod to prevent movement of the slide bearing on the

- rod in one direction but permitting movement in the opposite direction, said retractable member adapted to be manually operated to disengage the same from the rod whereby the slide bearing 5 may be manually moved in said opposite direction and away from the gauge plate.
4. A slicing machine comprising a gauge member, a slicing knife, a substance feeder, said substance feeder and said slicing knife being relatively 10 movable transversely whereby to bring the substance feeder alternately into alignment with the gauge member and with the slicing knife, said substance feeder being movable forward toward the gauge member and slicing knife through a given range of feeding travel, means for yieldingly urging the feeder forward, said means being inactive and without effective energy with respect to the feeder when the feeder is aligned with the slicing knife, and means operatively controlled by the relative transverse movement of the substance feeder and the knife for supplying effective energy to the urging means to operate the feeder when the feeder is aligned with the gauge member.
5. A slicing machine comprising a gauge member, a slicing knife, a substance feeder, said substance feeder and said slicing knife being relatively 15 movable transversely whereby to bring the substance feeder alternately into alignment with the gauge member and with the slicing knife, means yieldingly urging the substance feeder forward toward the gauge member when the feeder is in alignment with the gauge member, means for balancing the force exerted by said urging means on the feeder, and means operated by the urging means for operating said last mentioned means when the feeder is aligned with the slicing knife.
6. A slicing machine comprising a gauge member, a slicing knife, a substance feeder, said substance feeder and said slicing knife being relatively 20 movable transversely whereby to bring the substance feeder alternately into alignment with the gauge member and with the slicing knife, energy receiving means for yieldingly urging the substance feeder longitudinally forward toward the gauge member when the feeder is in alignment with the gauge member, and means operatively controlled by the relative transverse movement of the substance feeder and the knife and operable when the feeder is aligned with the gauge member to increase the energy of said urging means, said last means being operatively connected to the urging means to decrease the energy of said urging means when the feeder is aligned with the slicing knife.
7. A slicing machine comprising a gauge member, a knife member, a substance feeder, said substance feeder and said knife member being relatively 25 movable transversely whereby to bring the substance feeder alternately into alignment with the gauge member and with the knife member, said substance feeder being movable forward toward the gauge member and knife member through a given range of feeding travel, means

for yieldingly urging the feeder forward, and means operatively controlled by the relative transverse movement of the substance feeder and the knife for disconnecting a portion of said urging means from the feeder when the feeder is aligned with one of said members and for reconnecting said portion to the feeder when the feeder is aligned with the other of said members.

8. A slicing machine comprising a gauge member, a slicing knife, a substance feeder, said substance feeder and said slicing knife being relatively 30 movable transversely whereby to bring the substance feeder alternately into engagement with the gauge member and the slicing knife, said substance feeder being movable forward toward the gauge member and slicing knife through a given range of feed travel, resilient means for yieldingly urging the feeder forward, said means being without a sufficient supply of energy with respect to the feeder when the feeder is aligned with the slicing knife, and means operatively controlled by the relative transverse movement of the substance feeder and the knife for supplying an additional increment of energy to said 35 resilient means to operate the feeder when the feeder is aligned with the gauge member.

9. A slicing machine comprising a gauge member, a slicing knife, a substance feeder, said substance feeder and said slicing knife being relatively 40 movable transversely whereby to bring the substance feeder alternately into engagement with the gauge member and the slicing knife, said substance feeder being movable forward toward the gauge member and slicing knife through a given range of feed travel, resilient means for yieldingly urging the feeder forward, said means being without a sufficient supply of energy with respect to the feeder when the feeder is aligned with the slicing knife, means operatively controlled by the relative transverse movement of the substance feeder and the knife for supplying an additional increment of energy to said 45 resilient means to operate the feeder when the feeder is aligned with the gauge member, and means for limiting the increment of energy added during each slicing operation.

10. A slicing machine comprising a gauge member, a rotary slicing knife, a substance supporting carriage reciprocable transversely of the knife and alternately into alignment with the gauge member and the slicing knife, a substance pusher carried by the carriage and movable toward and from the knife, means for yieldingly urging the substance pusher toward the knife, said means being inactive and without effective energy with respect to the substance pusher when the pusher is aligned with the slicing knife, and means operatively controlled by the transverse movement of the carriage for supplying effective 60 energy to the urging means to operate the substance pusher when the pusher is aligned with the gauge member.
